UNITED STATES PATENT OFFICE

LENNOX ROBERTSON, OF CARDIFF, WALES

MEANS FOR HOLDING STAIR CARPETS AND RUNNERS IN POSITION

Application filed June 10, 1930, Serial No. 460,265, and in Great Britain June 22, 1929.

This invention relates to stair-carpet fastening devices and aims to provide improved means or fittings for adjustably holding in position the ends of runner carpets to stairs, landings or the like, and for assisting the folding, stretching and fixing of such carpets to risers above and below winding stair treads.

Clamp rods are generally recognized to offer the best and strongest way of holding stair carpets in place since they allow a tight stretching of the material. A difficulty with them however is met in the case of a stair of winding treads where occurrent gathers or fullness above and below the treads cannot be disposed of. As well known, winding stair treads are narrow at the inside and wide at the outside of the turn and this difference is often so great that the amount of carpet necessary to be gathered in at one side against the riser cannot be brought into a single triangular fold. Moreover, the length of the fold measured along the clamp rod may vary with the form of the stairs or pitch of the spiral.

For these reasons, means heretofore proposed for fastening carpets onto winding stairs have not generally proved successful, there being no adequate provision for adapting the fit to different requirements and at the same time keep all gathers unobtrusive or hidden from sight.

This invention makes use of a light but rigid metal lath, which is advantageously adjustable longitudinally, supported by its ends in stout wire-hinge fittings which may themselves be longitudinally adjustable in brackets secured to a riser, thereby enabling adjustment and placement to be made so as to ensure that all parts will be obscured and yet permit the whole to be moved laterally one way or the other to adjust the line of the carpet. The range of utility of a set of the fastening members is thus made very large and may be increased by making the end hinge fittings removable from the lath and also from their brackets so that other end fittings can be applied to adapt the lath for use in securing a carpet at both the foot

and head of a stairway and also at opposite ends when used as a floor runner.

In order for the invention to be more readily understood and employed, it will now be further described with reference to the appended drawings, in which:

Fig. 1 illustrates a preferred embodiment of the fitting or device in front elevation view;

Fig. 2 is an elevation thereof on a larger scale;

Fig. 3 is a transverse section of a stair riser and tread illustrating the manner of fastening a carpet thereto with gathering in accommodation to a winding case;

Fig. 4 is a front view illustrating the carpet fold in dotted lines;

Fig. 5 illustrates a modification adapted more especially to hold the carpet at the head of a stair; and

Figs. 6 and 7 are enlarged views of said modification corresponding to Figs. 2 and 3 of the preferred embodiment.

The grip device shown in Figs. 1, 2, 3 and 4 consists of a thin steel lath 1, which is corrugated or ribbed along its length as represented at 2 for stiffening and strengthening. This lath has end support on hinge fittings 3 of stout spring steel wire, each in this instance having a portion 36 doubled upon itself providing a stud slidable into the corrugation or a hole at the end of the lath and embraced by a metal clip 22 for securing thereto. These wire fittings have end portions 3a extended in parallel relation to and spaced from the lath, which are removably as well as pivotally and slidably fastened to a stair riser 4 by engagement in sleeve-brackets 5 screwed to the riser. Each moreover has a free end portion 39 bent parallel to and slightly apart from the lath to provide a grip for the carpet.

In application, as will be understood, these fittings with their gripping ends are held out in a more or less horizontal position to pass the carpet between said ends and the lath. The reserve amount of carpet represented by the fold 32 in Figs. 3 and 4 due to the turn or wind of the stairs is then gathered or drawn up behind the lath in

front of the riser with an extension from below and under the wires as shown, after which the lath is swung and pressed down, thereby stretching the carpet tightly, and is then secured by the application of a clamp-rod 31, (see Fig. 3) or the like. A double bending in the form of a crank as represented at 23 will allow for the fold of the carpet to be brought up while allowing the major part of the wire to be disposed well behind the carpet.

From the drawings it will be apparent that the distance between the wire fittings can be adjusted to the actual width of the carpet and further that the lath and wires as a whole can be readily moved laterally with the carpet by sliding the ends of the wires in their brackets 5.

Figs. 5, 6 and 7 illustrate how the invention may be applied to hold the top end of a stair carpet under the nose 9 of a landing 10. This is shown done by substituting support wires 33 for the wires 3 of the first described form. These substitute wires are substantially like the former and differ therefrom only in shape as represented, having corresponding end portions 33^a fixed in brackets 55, corresponding double bends 36^x fitting in the lath 1 and corresponding crank bends 23^x allowing for the carpet fold. In conjunction therewith, there is affixed to the stair riser, a pair of bell-crank hasps 28 pivoted at 29 so as to be engaged over and hold said wires (33) in tensioned position against the riser. In this case, the reserve length or back-doubled end of the carpet should be placed over the lath 1 and drawn down therebehind. It may if desired be drawn down over the next tread or even further, and a clamping rod 31 as ordinarily used may then be applied to hold the carpet at the juncture between the riser and tread, as shown in Fig. 7.

What I claim is:—

1. A carpet fastening device, comprising a flat metal bar having axial openings in its ends, lateral swing-arms at the ends of the bar having projections slidably fitting into said openings thereof and extremital portions parallel thereto providing swivel pins, and supporting bracket-members having swivel-holes into which said extremital portions of the arms slidably fit in a hinged connection; whereby said arms are rendered removable from and adjustable toward and from each other in both said bar and said bracket-members.

2. A stair-carpet fastening device, comprising a flat metal bar having axial openings in its ends, lateral swing-arms formed by wire pieces at the ends of the bar having double-bend portions slidably fitting into said openings thereof and extremital portions bent parallel thereto providing swivel pins, clips engaging the arms in place to

the bar, and affixable bracket-members having swivel holes into which said extremital portions of the arms slidably fit in a hinge connection; said arms being removable from and adjustable in both said bar and the bracket-members.

3. Carpet holding means comprising a flat metal rod, swing-arm members removably connected with the ends of the bar in a longitudinally movable relation, and support-brackets to which said hinge-members are removably connected on a slide pivot parallel to the bar; whereby the hinge members are rendered adjustable toward and from each other on both said bar and brackets.

4. A strip-carpet holding device, comprising an extensible flat metal bar, swing-members in the form of bent wire fittings removably connected with the ends of the bar in a movable relation longitudinally thereof, and support-brackets to which said members are removably connected on a slide pivot parallel to the bar; said bar and said members being adjustable separately with respect to the width and marginal line of the carpet.

5. A carpet fastening device, comprising a flat metal bar having a stiffening rib, lateral swing-arms removably connected at the ends of said bar in movable relation longitudinally thereof, and support-brackets in which said arms are removably pivotally connected for slide movement in direction parallel to the bar, whereby said arms may be adjusted toward and from each other upon both said bar and said brackets.

6. A carpet fastening device, comprising a rigid flat metal bar around which the carpet is looped, lateral swing-arms affixed to the ends of said bar by projections thereof fitting slidably into axial openings in the same, supporting brackets into which projections at any end of said arms parallel with the bar slidably fit in a hinge connection, and projections at the other end of said arms also parallel with the bar providing spring-clip members.

Signed at Cardiff, Wales, this 26th day of May, 1930.

LENNOX ROBERTSON.
